UNITED STATES PATENT OFFICE

155,133

DESIGN FOR A FISH LURE

Harold W. Dow, Metamora, Mich.

Application August 10, 1948, Serial No. 148,019

Term of patent 7 years

(Cl. D31—4)

To all whom it may concern:

Be it known that I, Harold W. Dow, a citizen of the United States and resident of the city of Metamora, county of Lapeer, and State of Michigan, have invented a new, original, and ornamental Design for Fish Lures, of which the following is a specification, reference being had to the accompanying drawings, forming part thereof.

Fig. 1 is a top plan view of a fish lure showing my new design;

Fig. 2 is a side elevational view of said lure;

Fig. 3 is a front elevational view of said lure.

The dominant features of my design reside in the portions shown in full lines.

I claim:

The ornamental design for a fish lure, as shown and described.

HAROLD W. DOW.
